UNITED STATES PATENT OFFICE.

DAVID S. KENNEDY, OF BROOKLYN, NEW YORK, ASSIGNOR TO MERGENTHALER LINOTYPE COMPANY, A CORPORATION OF NEW YORK.

TYPOGRAPHICAL MACHINE.

1,231,908.

Specification of Letters Patent.

Patented July 3, 1917.

Application filed September 23, 1915. Serial No. 52,145.

To all whom it may concern:

Be it known that I, DAVID S. KENNEDY, a citizen of the United States, residing at Brooklyn, in the county of Kings and State 5 of New York, have invented certain new and useful Improvements in Typographical Machines, of which the following is a specification, reference being had therein to the accompanying drawing.

- 10 My invention relates to typographical machines, such as linotype machines of the general organization represented in Letters Patent of the United States to O. Mergenthaler, No. 436,532, wherein circulating matrices are released from a magazine in the order in which their characters are to appear in print and then assembled in line, the composed line transferred to the face of a mold, the mold filled with molten metal to form a 15 slug or linotype against the matrices which produce the type characters thereon, and the matrices thereafter returned through a distributing mechanism to the magazine from which they started.
- 20 25 In such machines, the release of the matrices from the magazine is effected by means of escapements acting through openings in the bottom thereof, and in some instances these escapements are attached directly to the magazine, while in other instances they are supported independently thereof. When the escapements are thus independently supported, it becomes necessary to lock the matrices in the magazine before it is removed 30 from the machine, as otherwise the matrices would be free to escape therefrom. This is ordinarily insured against by employing devices which will prevent the removal of the magazine until the matrices have first been 35 locked therein, such as shown in the U. S. Patents Nos. 829,868 and 1,101,282 to Thomas S. Homans. In the first of these patents, in effecting the removal of the magazine, it is lifted out of engagement 40 with the escapements, and the locking devices above mentioned serve to prevent the premature raising of the magazine; while in the second patent, before the magazine is removed, the escapements are lowered out of 45 operative relation thereto, and the locking devices serve to prevent the movement of the escapements, as distinguished from that of the magazine.
- 50 My present invention is intended to pro-

vide devices in either class of machine, 55 whereby the locking of the matrices in the magazine is effected automatically during its removal and so as to avoid the delay incident to the old practice and to relieve the operator of any attention on his part. In 60 the present instance, and as will be fully pointed out later, this automatic locking of the matrices is controlled by devices which hold the magazine in operative position or in operative relation to the escapements. 65

In the accompanying drawings, I have shown my invention merely in preferred form and by way of example and as applied to the particular style of machine mentioned, but obviously many alterations and 70 variations may be made therein and in its mode of application, which will still be comprised within its spirit. Thus, it may be applied to other forms of typographical machines, such as typesetters, and the like, 75 which handle type or dies instead of matrices. Generally speaking, I desire it to be understood that I do not limit myself to any specific form or embodiment, except in so far as specified in the claims. 80

Referring to the drawings:

Figure 1 is a perspective view of the lower part of a linotype machine with my invention applied thereto;

Fig. 2 is a vertical section through the 85 lower end of the magazine and the escapements, and showing the magazine unlocked and ready for removal;

Fig. 3 is a similar view showing the magazine locked in position; and 90

Fig. 4 is a section on the line 4—4 of Fig. 3.

The magazine A, wherein the matrices X are stored, comprises as usual the side plates A⁶ and the edge plates or bars A⁵, the side plates being formed in their inner or opposing faces with the converging grooves A¹ providing channels for the matrices. As illustrated herein, the magazine is removably supported in the machine upon the fixed 100 frame B, which also gives independent support to the escapements C, which pass through openings A⁷ in the bottom plate of the magazine to control the release of the matrices therefrom, and are operated from 105 the keyboard in the usual way through the vertical reeds C¹.

In the present instance, therefore, the dis-

engagement of the escapements from the magazine takes place when the latter is raised from its supporting frame B for removal, as distinguished from swinging the escapements out of operative relation thereto, and such disengagement may be prevented by holding or locking the magazine in operative position upon the frame. Devices subserving this purpose are shown herein and comprise a pair of plates D attached to the opposite edges of the magazine by screws A² passing loosely through fore-and-aft elongated slots D¹ in the plates so as to permit them to be slid forwardly and backwardly on the magazine. At their forward ends, the plates D are provided with hooks D² to coöperate with pins B¹ projecting inwardly from the opposite sides of the frame B, the hooks being of such extent that in the forward position of the plates they engage beneath the pins and prevent the raising of the magazine, as illustrated in Fig. 3, while in the rearward position of the plates, they clear the pins and permit such raising, as indicated in Fig. 2. If desired, the plates D may be provided with grip pieces D⁸ to facilitate their movement.

At its upper side the magazine is also provided with a comb plate E arranged to slide vertically between a pair of fixed guide bars A⁴ so as to project its teeth E¹ into, or withdraw them from, the magazine channels. In the lower position of the plate, its teeth stand across or in front of the upper ears of the leading matrices in the magazine channels, as indicated in Fig. 2, thus preventing their escape therefrom; and in its upper position, the teeth are withdrawn from the magazine channels or out of the path of the matrices, as shown in Fig. 3, thus permitting their escape. The transverse movements of the comb plate E are effected by the sliding plates D, the former being provided at its opposite ends with projecting pins E² engaging in inclined cam slots D³ in the upper edges of the latter. The slots serve by their coöperation with the pins to raise and lower the comb plate as the plates D are shifted forwardly and backwardly, respectively, they being plain or straight at the front, as at D⁴, so as to maintain the comb plate depressed when the plates D are in their rearward position. When the plates D are slid rearwardly to disengage the hooks D² from the pins B¹ and unlock the magazine for removal, the comb plate E is shifted automatically to locking position, that is, with its teeth E¹ projecting into the magazine channels; and when the plates D are slid forwardly to lock or re-lock the magazine in position, the comb plate is shifted upwardly automatically to unlocking position or to withdraw its teeth from the magazine channels.

65 In short, the arrangement is such that the

locking and unlocking of the magazine effects the unlocking and locking of the matrices therein, respectively.

As shown in Figs. 2 and 3, the rear faces of the teeth E¹ are beveled or inclined, as at E⁵, so that as they are projected into the magazine channels by the downward movement of the plate E, they will push the matrices rearwardly a slight distance and thus provide clearance between the matrices and the escapements as the magazine is removed from or replaced in the machine. The beveled surfaces also facilitate the co-operation of the teeth with the matrices.

In order to maintain the plate E in its locking position when the magazine is removed, the latter is provided with spring-pressed pins A³, located in the edge bars A⁵, and arranged to enter holes or apertures D⁷ in inturned flanges D⁵ of the plates D, when the latter occupy their rearward or unlocking position. Normally the pins A³ are prevented from entering the holes D⁷ by cam pieces B² projecting upwardly from the frame B, but when the magazine is lifted from the frame, the pins A³ are removed from the control of the cam pieces and are thus allowed to enter the holes D⁷ and lock the plates D against movement. Similarly, when the magazine is replaced upon the frame B, the cam pieces B² re-engage the pins A³ and push them out of the holes D⁷, thus releasing the plates D and allowing them to be moved forwardly to lock the magazine in place. The effect of this arrangement is that the matrix retaining plate E is automatically locked and unlocked in its active position as the magazine is removed from and replaced in the machine, respectively. It will be noted that the inturned flanges D⁵ are also formed with slots D⁶ opening into holes D⁷ to enable them to clear the cam pieces B² as the plates D are shifted forwardly and backwardly.

As previously stated, I have shown my improvements merely in preferred form and by way of example, but obviously many changes and modifications will suggest themselves to those skilled in the art without departing from the scope of my invention.

Having thus described my invention, its construction and mode of operation, what I claim and desire to secure by Letters Patent of the United States is as follows:

1. In a typographical machine, the combination with a magazine to contain the matrices and a series of escapements to control their release therefrom, one of said parts being movable out of operative relation to the other, of a locking device for holding the magazine and escapements in operative relation but movable at will to release said parts for separation, and a matrix locking device permanently mounted on the magazine and

- connected to the other locking device so as to be moved to active position as the magazine and escapements are unlocked from each other preparatory to their separation.
- 5 2. In a typographical machine, the combination with a magazine to contain the matrices and a series of escapements to control their release therefrom, one of said parts being movable out of operative relation to the other, of a locking device for holding the magazine and escapements in operative relation but movable at will to release said parts for separation, a matrix locking device permanently mounted on the magazine, and 10 connections between the two said locking devices whereby the unlocking of the magazine and escapements preparatory to their separation effects the locking of the matrices in the magazine and whereby the locking or 15 relocking of the magazine and escapements after they are restored in operative relation to each other effects the unlocking of the matrices in the magazine.
3. In a typographical machine, the combination of a magazine to contain the matrices, a series of escapements to control the release of the matrices therefrom, a device for locking the magazine and escapements in operative relation to each other, and means permanently mounted on the magazine and positively actuated by said device for pushing the matrices back within the magazine to allow them to clear the escapements when such parts are disengaged.
- 35 4. In a typographical machine, the combination of a magazine to contain the matrices, a series of escapements to control the release of the matrices therefrom, a movable locking device to hold the magazine and escapements in operative relation to each other, a movable matrix locking device permanently mounted on the magazine and constructed so as to shift them rearwardly therein as it is moved to active position, and positive operative connections between the two said locking devices.
5. In a typographical machine, the combination with a magazine to contain the matrices, and a series of escapements to control the release of the matrices therefrom, one of said parts being movable out of operative relation to the other, of releasable locking means to prevent the movement of said part, a matrix locking device movable to active position by the release of said locking means, and automatic means for holding said locking device in its active position as the magazine and escapements are moved out of operative relation to each other.
- 60 6. In a typographical machine, the combination with a magazine to contain the matrices, and a series of escapements to control the release of the matrices therefrom, one of said parts being movable out of operative relation to the other, of releasable locking

- means to prevent the movement of said part, a matrix locking device movable to active position by the release of said locking means, and means for holding the locking device in its active position, the said means being rendered active and inactive as the magazines and escapements are moved out of and into operative relation to each other, respectively. 70
7. In a typographical machine, the combination of a removable magazine, releasable means to hold the magazine against removal, a matrix locking device carried by the magazine and operatively connected to said holding means so as to be movable to active position as they are released, and means for holding the locking device in its active position, the said means being rendered active and inactive as the magazine is removed from and replaced in the machine, respectively. 75
8. In a typographical machine, the combination of a removable magazine to contain the matrices, means carried thereby for locking it in the machine, and a device controlled by said means for locking the matrices in the magazine. 80
9. In a typographical machine, the combination of a removable magazine to contain the matrices, means carried thereby for locking it in the machine, a device controlled by said means for locking the matrices in the magazine, and means for holding the matrix locking device in active position when the magazine is removed from the machine. 85
10. The magazine A provided with a movable plate D having the locking hook D² and the cam grooves D³, and the matrix locking plate E having portions engaging in the cam grooves D³. 90
11. The magazine A provided with the movable locking plate D, the movable comb plate E operatively connected to the plate D, and the detent A³ to hold the plate D in its unlocking position. 95
12. In a typographical machine, the combination of the supporting frame B provided with the projecting pin B¹ and the cam plate B², with the magazine A removably mounted upon the supporting frame 115 and provided with the movable plate D having the locking hook D² to coöperate with the pin B¹, and also provided with the detent A³ controlled in its action by the cam plate B². 110
13. In a typographical machine, the combination of a removable magazine, locking means to hold it in operative position in the machine and releasable at will to permit its removal, a matrix locking device permanently mounted on the magazine, and means whereby said locking device is moved to active position as the magazine is unlocked. 120
14. In a typographical machine, the combination of a removable magazine, a mov- 125

able locking device to hold it against removal, a movable matrix locking device permanently mounted on the magazine, and connections between the two locking devices 5 whereby the locking and unlocking of the magazine effects the unlocking and locking of the matrices in the magazine, respectively.

15. In a typographical machine, the combination of a removable magazine, a releasable locking device to hold it against removal, and means controlled by said locking device for pushing the matrices back within the magazine.

16. In a typographical machine, the combination of a removable magazine, a releasable locking device to hold it against removal, a matrix locking device movable to active position by the release of the maga-

zine locking device, and automatic means for holding said matrix locking device in its active position when the magazine is removed. 20

17. In a typographical machine, the combination of a removable magazine, a releasable locking device to hold it against removal, a matrix locking device movable to active position by the release of the magazine locking device, and means for holding said matrix locking device in its active position, the said means being rendered active and inactive as the magazine is removed 25 from and replaced in its operative position in the machine.

In testimony whereof, I have affixed my signature.

DAVID S. KENNEDY.
